UNITED STATES PATENT OFFICE.

HENRY UNTERMEYER, OF NEW YORK, N. Y.

DESIGN FOR A WATCH-CASE.

SPECIFICATION forming part of Design No. 15,121, dated July 1, 1884.

Application filed May 5, 1884. Term of patent 7 years.

To all whom it may concern:

Be it known that I, HENRY UNTERMEYER, a citizen of the United States, residing at New York, in the county and State of New York, have invented a Design for Watch-Cases, of which the following is a specification.

The design which is the subject of this application is illustrated in the accompanying drawings, in which—

Figure 1 is a plan view, and Fig. 2 a sectional view, of the design on the line *x-x* of Fig. 1.

A denotes a conventional star, which is the center of the design, in which any ornament, 15 D, may be set. The conventional star A is placed upon a ground of leaves, B, which is larger than the star A, and of corresponding shape. Between the points or leaves of the part B are the projections C, the whole being 20 in relief, as shown.

In the drawings, the design is shown supplemented by concentric circles and by lathe-work; but these are not to be regarded as constituting any part of the invention sought to 25 be protected hereby.

What I claim as my invention, and desire to secure by Letters Patent, is—

1. A design for watch-cases, consisting of the conventional star A and the larger star, B, the points of which represent leaves, the star A occupying the central field of the star B, all being in relief, substantially as shown and described.

2. A design for watch-cases, consisting of the conventional star A and the larger star, B, composed of leaves, and having between its points ornamental projections C, the star A occupying the center of the star B, all being in relief, substantially as shown and described.

3. A design for watch-cases, consisting of the star A, containing the ornament D, the larger star, B, representing leaves, and having between its points the ornamental projections C, and the star A occupying the center of the star B, all being in relief, substantially as shown and described.

Witness my hand this 6th day of May, A. D. 1884.

HENRY UNTERMEYER.
